UNITED STATES PATENT OFFICE.

OLIVER D. H. BENTLEY, OF NEW YORK, N. Y., ASSIGNOR TO E. W. BLISS COMPANY, OF BROOKLYN, NEW YORK, A CORPORATION OF WEST VIRGINIA.

TURBINE.

935,956.

Specification of Letters Patent.

Patented Oct. 5, 1909.

Application filed August 5, 1909. Serial No. 511,310.

To all whom it may concern:

Be it known that I, OLIVER D. H. BENTLEY, a citizen of the United States, residing in the borough of Brooklyn, county of 5 Kings, city and State of New York, have invented certain new and useful Improvements in Turbine-Engines, of which the following is a specification.

This invention relates to steam or other 10 turbines wherein the jet or stream of fluid is caused to impinge two or more times against the same series of rotor vanes or buckets.

The steam is first directed against the 15 rotor through a nozzle,—preferably an expanding nozzle, so as to secure the maximum velocity in the jet or current which is impelled against the vanes,—enters the buckets at one side, and by reason of the curvature 20 of the buckets is discharged therefrom at the other side; the steam thus backwardly directed from the buckets is caught in a curved passage, chamber or pocket, which turns the current back and directs it again 25 into the rotor buckets; the steam may be thus returned two or more times to the rotor by the provision for this purpose of two or more reversing chambers or passages. Such reversing chambers have heretofore 30 been applied in various arrangements with relation to rotors having their buckets formed either upon the periphery or upon one or both faces of their rotor wheel or disk. As applied to lateral buckets, the reversing passages have been arranged in the 35 same plane as the rotor and curving both inwardly and outwardly of the path of the buckets. As applied to peripheral buckets, the stationary reversing passages have been 40 applied on alternately opposite sides of the plane of the rotor, being located in cylindrical developments to either side of the circular path of the buckets. As applied with tangential peripheral buckets, such reverse 45 passages or chambers have also been arranged in tangential planes in advance of the jet nozzle so as to whirl the same through approximately a half circle, completing the semicircular whirl given it in the rotor 50 buckets, with the result that the steam describes approximately a distorted helix, passing repeatedly between the rotor buckets and the stationary reverse passages.

My invention provides a new and improved construction and arrangement of re-

verse passages or chambers applicable to rotors having peripheral buckets opening tangentially and formed with rounded bottoms. According to my invention the steam entering such buckets at one side is whirled 60 through approximately a half circle and is discharged into a reversing chamber located in the plane of the rotor and confined to the opposite half thereof from that in which the jet first enters the buckets; in other words in 65 the plane of the discharge sides of the buckets. The reverse passage curves outwardly in this plane, and sweeping around, returns in the same plane and discharges into the rotor buckets at a point further advanced 70 and on the same side as the discharge therefrom. The steam thus returned to the buckets executes therein another half turn and is discharged therefrom upon the opposite side (being the same side at which it originally 75 entered from the jet nozzle), and at this point of discharge another reversing passage is preferably provided identical with the first except that it is located in a more advanced position, and in a plane coinciding 80 with that in which the jet originally entered the buckets. There may be as many such reversing passages or chambers as are desirable to afford suitable efficiency.

The accompanying drawings show the 85 preferred embodiment of my invention.

Figure 1 is a diametrical cross-section in the plane of the line 1—1 in Fig. 2; Fig. 2 is a vertical section in a plane transversely to the axis of rotation, the casing being in 90 section on the line 2—2 in Fig. 1; Fig. 3 is a partially diagrammatic view being mainly an elevation of the rotor with the steam inlet and reversing chambers in their relation thereto, viewed in the direction of arrow 3; Fig. 4 is an elevation of a fragment of the 95 rotor partly dissected away to show one bucket in tangential section; Fig. 5 is a fragmentary section of the rotor through the bottoms of the buckets; Figs. 6 and 7 100 are sectional views showing two modifications of the reversing chamber.

Let A designate the turbine wheel or rotor mounted upon a shaft B which will be hung in suitable bearings.

C is the casing having steam inlets at D D, with an expanding nozzle E communicating with each inlet to direct the steam into the buckets of the rotor. Any suitable labyrinthine or other packing may be applied to 110

prevent leakage of steam from the casing around the rotor shaft, such packings being well understood, and being omitted from the drawings for the sake of clearness.

5 The rotor buckets F F are of well known construction, being formed in the periphery of the rotor or bucket wheel and in tangential planes and with rounded bottoms, so that the current of steam discharged into the 10 successive buckets at one side thereof is whirled against the semicircular bottoms of the buckets and thrown out therefrom tangentially in a direction contrary to and substantially parallel with its inflowing movement. The specific construction of buckets 15 is immaterial, but I prefer to construct them in the manner set forth in detail in my application No. 494,450 filed May 6, 1909. The essential construction of the buckets is that 20 shown in Figs. 4 and 5, being formed in successive tangential planes with partitions *a* between them, as thin as is practicable, and with bottoms *b* which are rounded or preferably semicircular.

25 Adjacent to each nozzle E is arranged a reverse chamber G. This chamber may conveniently be constructed with its curved wall of a strip of sheet or plate metal bent to the proper curve, and with its sides formed 30 by flat metal sheets or plates cut to the proper outline and united to the bent metal strip which connects them, so as to form a flat-sided box of curved outline and open on its side next the rotor. This light construction 35 is admissible for a turbine of the velocity type wherein the steam before impinging upon the rotor is reduced to practically atmospheric pressure. The reversing chamber may be fastened within the casing in any 40 suitable manner, with its open side as close to the rotor as is consistent with proper mechanical clearance.

The width of the reversing chamber should 45 not exceed but preferably should substantially equal one-half the width of the buckets. The location of the reversing chamber is such that the steam entering the buckets from the nozzle, and which is given a half turn in the buckets, shall on emerging therefrom enter the reversing chamber as shown in Fig. 2, and whirling around in this chamber, shall be directed thereby tangentially against and into the buckets at a point suitably removed from the nozzle. The steam 55 is thus returned by the reversing chamber to the buckets on the same side thereof from which it first emerged therefrom. That is to say, if the nozzle directs the steam into the buckets at the right hand side, it is given 60 a half turn therein and enters the reversing chamber from the left hand side of the buckets, and this chamber again returns the steam to the buckets on their left hand side. It is preferable that the reversing chamber 65 shall curve forwardly and direct the steam

against the rotor at a point in advance of that at which it passes from the rotor into the reversing chamber, as shown in Fig. 2; but it is admissible to reverse this arrangement so as to curve the stream of steam backwardly and then direct it forwardly against the rotor at a point to the rear of that from which it emerged from the rotor bucket, as shown in Fig. 6. The use of one reversing chamber thus constitutes a double stage turbine. For a triple stage turbine it is only necessary to add another reversing chamber, the latter being shown at G² in Fig. 2. This chamber is located in the same plane as the nozzle E, so that it covers the opposite half 80 of the bucket openings from that covered by the first chamber G. This is clearly shown in Fig. 3, which shows somewhat diagrammatically the course of the current of steam in entering and leaving the successive reversing chambers G¹ G². Fig. 3 also shows a third reversing chamber G³ which is applied in the same plane as G¹. A fourth chamber might be added in the same plane as G². The number of reversing chambers to be 85 used in any given case is limited only by the consideration of efficiency. Thus in a multiple stage turbine the even numbered reversing chamber or chambers will be placed against the same side of the rotor as the nozzle, while the odd numbered reversing chambers are placed upon the opposite side, the even numbered and odd numbered chambers occupying planes parallel with one another and coinciding with the opposite halves 90 of the open sides of the buckets of the rotor.

It is common to make rotors of the character described with partitions in the buckets around which the steam may flow, and my invention is applicable with this construction 105 as well as with that shown. Such partitions, however, are unnecessary, since the centrifugal effect of the steam prevents interference between the entering and emerging portion of the current of steam. In like manner 110 the reversing chamber may be devoid of any partition, as shown in Figs. 2 and 6, or it may have a central partition H, as shown in Fig. 7. The reversing chambers may be mounted in any suitable way. For example, 115 in Fig. 2 screws c c are shown for fastening them to the casing.

I claim as my invention:—

1. In a turbine engine, a rotor having peripheral buckets opening tangentially and formed with rounded bottoms, and a tangential jet nozzle discharging into said buckets on one side thereof, whereby the fluid is whirled within the buckets and discharged backwardly from the opposite side thereof, combined with a reversing passage arranged to receive such discharge and return it to the buckets at another point, said passage located in a plane coinciding with the rotor 120 and corresponding to the side thereof from 125

which such discharge occurs, whereby the fluid is returned to the buckets on that side, and receives thereupon in the buckets a whirl in the contrary direction.

5 2. In a turbine engine, a rotor having peripheral buckets opening tangentially and formed with rounded bottoms, and a tangential jet nozzle discharging into said buckets on one side thereof, whereby the fluid is whirled within the buckets and discharged 10 backwardly from the opposite side thereof, combined with a reversing passage arranged to receive such discharge and return it to the buckets at another point, said passage located 15 in a plane coinciding with the rotor and corresponding to the side thereof from which such discharge occurs, whereby the fluid is returned to the buckets on that side, and receives thereupon in the buckets a whirl 20 in the contrary direction.

3. In a turbine engine, a rotor having peripheral buckets opening tangentially and formed with rounded bottoms, and a tangen-

tial jet nozzle discharging into said buckets on one side thereof, whereby the fluid is 25 whirled within the buckets and discharged backwardly from the opposite side thereof, combined with a reversing passage arranged to receive such discharge and return it to the buckets at another point, said passage located 30 in a plane coinciding with the rotor and corresponding to the side thereof from which such discharge occurs, whereby the fluid is returned to the buckets on that side, and receives thereupon in the buckets a whirl in 35 the contrary direction, and a second similar reversing passage arranged to receive the fluid discharged from the buckets after such second whirl.

In witness whereof, I have hereunto signed 40 my name in the presence of two subscribing witnesses.

OLIVER D. H. BENTLEY.
